CLAIM

The ornamental design for surface ornamentation for a holster system, as shown and described.

DESCRIPTION

FIG. 1 is a top, right perspective view of a surface ornamentation for a holster system in accordance with my new design;

FIG. 2 is a bottom, left perspective view thereof;

FIG. 3 is a front view thereof;

FIG. 4 is top, right, perspective view of a surface ornamentation for a holster system in accordance with my new design;

FIG. 5 is a bottom, left perspective view thereof; and,

FIG. 6 is a front view thereof.

The broken lines in the figures illustrate portions of the surface ornamentation for a holster system that form no part of the claimed design. The dash-dot-dash lines surrounding the surface ornamentation for a holster system in certain FIGS. 1–6 indicate a boundary line.
